United States Patent Office.

CHARLES S. CHAFFEE AND ALEXANDER WAHLIG, OF BIRMINGHAM, CONNECTICUT,
ASSIGNORS TO THEMSELVES AND J. M. GOULDING, OF SAME PLACE.

Letters Patent No. 100,723, dated March 15, 1870.

IMPROVED METHOD OF SECURING SOLES TO BOOTS AND SHOES.

The Schedule referred to in these Letters Patent and making part of the same.

To all whom it may concern:

Be it known that we, CHARLES S. CHAFFEE and ALEXANDER WAHLIG, of Birmingham, in the county of New Haven, and State of Connecticut, have invented a new and useful Improvement in Attaching Soles to Boots and Shoes; and we do hereby declare that the following is a full, clear, and exact description thereof, which will enable others skilled in the art to make and use the same, reference being had to the accompanying drawings forming part of this specification.

This invention relates to improvements in attaching soles to boots and shoes; and consists in attaching them by screws passed through eyelets formed in or connected to an endless wire, which is laid in a channel cut in the sole to sink the wire below its surface, the said eyelets being made to coincide with the holes formed for the screws, and the said holes being large enough to permit the screws to be forced well down into them, so as to produce such tension on the wire as to cause it to hold the outer or half-sole snugly to the in-sole, between the holes.

The object of the invention is to so simplify the process of half-soling and heelng boots and shoes that have been worn, that persons unskilled in boot and shoe-making may readily attach them; also, to prevent the cutting of the in-soles by repeated pegging or sewing on the outer soles, now so common, the screws being placed so far apart that, no matter how often the re-soling may be done, the in-soles will not be damaged thereby.

Figure 1 is a plan of the bottom of a shoe with a half-sole attached by our improved mode, the eyelets being formed on the wire by bending it;

Figure 2 is a section through a part of the same;

Figure 3 is a section showing the eyelet formed of sheet metal, and attached to the wire by soldering or otherwise; and

Figure 4 is another section, in which the eyelet made of sheet metal is provided with a projection merely hooking on the wire.

Similar letters of reference indicate corresponding parts.

A is the half-sole;

A' the in-sole;

B the wire;

C the screws; and

D the eyelets.

The wire is made of suitable length to extend around the sole, near the edge, as shown, and to form an eyelet for each screw-hole.

The wire is in that case laid in a channel cut in the sole from one screw-hole to another. The screw-holes are made large enough at the top to admit the eyelets, so that the screws passing through them may draw them below the bottom of the groove, in order to hold the wire under great tension. In this way the sole may be secured very firmly with but few screws, and those at such distances apart that no damage will be done to the in-soles.

Instead of forming the eyelets on the wire as described, we may make them of sheet metal, in the shape of washers, and solder them to the wire passing across the holes in the sole, as shown in fig. 3, or we may connect them detachably, by hooking them to the wire, as shown in fig. 3, where E represents a hook or projection on one side of the eyelet, the same hooking over the wire.

Having thus described our invention,

We claim as new, and desire to secure by Letters Patent—

The herein-described method of securing soles of boots and shoes to the in-soles, by means of screws passing through eyelets formed on or attached to a wire which is laid in a channel extending around the sole, near the edges, the said eyelets fitting in the screw-holes which intersect the channel, and being forced in by the screws to tighten up the wire, all substantially as specified.

The above specification of our invention signed by us this 4th day of January, 1870.

CHAS. S. CHAFFEE.
A. WAHLIG.
